UNITED STATES PATENT OFFICE.

FREDRIC C. WEIR, OF CINCINNATI, OHIO.

SWITCH-STAND.

SPECIFICATION forming part of Letters Patent No. 351,235, dated October 19, 1886.

Application filed June 25, 1886. Serial No. 206,245. (No model.)

To all whom it may concern:

Be it known that I, FREDRIC C. WEIR, a resident of Cincinnati, in the county of Hamilton and State of Ohio, have invented certain new and useful Improvements in Switch-Stands, of which the following is a specification.

My invention relates to a switch-stand to be used in throwing rails for switching trains on railroad-tracks.

The object of my invention is, first, to provide a parallel-moving switch-stand, with a switch-bar having a direct connection to the switch-rails, with lever-connection, constructed so that a strong direct leverage may be obtained to move the rails.

Another object of my invention is to cheapen the construction and to thoroughly protect the parts from the weather.

Another object of my invention is to operate a switch-target simultaneously with the moving of the rails to show "safety" or "danger," as the case may be.

Other objects of my invention will be set forth in the description of the accompanying drawings, making a part of this specification, in which—

Figure 1 is a perspective view of my invention; Fig. 2, a top plan view with the top of the case broken off; Fig. 3, a detail view of the moving cylinder.

A represents a casing made in two sections provided with flanges 12, through which bolts 3 are passed to fasten the sections together.

4 represents a horizontal wing or flange projecting horizontally from the casing A. It is provided with holes 5 for spiking the same to sleepers or ties on which they rest.

6 represents a shaft journaled in bearings 7 8, formed in the casing to receive said shaft. 9 represents a drum rigidly connected to said shaft 6. 10 represents a worm-slot pierced in said drum 9. 11 represents a lever attached to the square end of said shaft 6 for rotating said shaft and drum.

12 represents the switch-bar moving longitudinally in ways or openings pierced through the ends of housing 13, formed on the casing A. 14 represents a lug rigidly attached to

said switch-bar 12, and projecting inwardly and resting within the spiral groove 10 of drum 9. As lever 11 is turned forward or backward the lug 14 is moved forward or backward by the spiral groove 10, reciprocating the switch-bar 12 in its bearings.

16 represents a bevel-gear mounted upon shaft 6 at the end of drum 9, meshing with a beveled quadrant, 17, which is keyed upon the target-shaft 18. This shaft journals in hub 19 at the top of housing 20, in which the bevel-segment 17 is inclosed or covered to protect it from the weather.

The casing A is cut away between the housing 20 and the bevel-gear 16. This housing 20 is practically an extension of the casing A.

21 represents a target attached to shaft 18.

The bevel-gears 16 17 are constructed so as to turn the target 21 one-fourth of a revolution at each throw of the lever, so that the target may indicate "danger" or "safety" to the respective tracks, according to the position of the switch, which is operated by lever 11.

22 represents the switch-rails, 24 25 the stationary rails of the tracks to be cut in and out by the movement of the switch-lever.

This form of construction of switch is very cheap and durable.

It is obvious that great power may be obtained in the direct thrust, capable of switching the movable switch-rails against the large amount of strain or resistance.

The casing A perfectly houses or protects all the working parts of the switch.

Having described my invention, what I claim is—

1. A switch-stand composed of a casing, A, having a housing, 13, at one side and a housing, 20, at one end, a bar, 12, provided with lug 14, said bar being passed through the side housing, 13, and connected at one end to the switch-rail, a spirally-grooved drum, 9, journaled in the casing and engaged with the lug 14 of bar 12, the lever 11 and bevel-gear 16 on the shaft of said drum, and the target-shaft 18, having a quadrant-gear, 17, located in the end housing, 20, and meshing with the gear on the drum-shaft, substantially as described.

2. A switch-stand composed of a casing, A, formed of two sections bolted together, one section having the recess 13 for the bar 12, and the separate compartment 20 for the signal, substantially as described.

In testimony whereof I have hereunto set my hand.

FREDRIC C. WEIR.
